VACUUM MACHINE

John M. Young, Brooklyn, N. Y., assignor to
 American Can Company, New York, N. Y., a
 corporation of New Jersey

Application August 22, 1931, Serial No. 558,820

9 Claims. (Cl. 198—209)

The present invention relates to a machine or apparatus for vacuumizing containers and has as an object the provision of a rotating container carrier valve mounted in an improved manner adjacent the vacuum chamber of such a machine whereby pressure of the valve against its valve seat is more even and more easily controlled.

The present invention is particularly adapted to the mounting of a tapered valve which engages a valve seat of corresponding shape and which maintains a seal for the vacuum chamber while rotating to carry cans into or out of the chamber. Provision is made for maintaining this proper seal between the engaged surfaces at all times while allowing for expansion of the valve as it becomes frictionally heated with use. This prevents binding of the valve in its valve seat and is a self-contained, automatic, compensating feature.

The principal object of the present invention is the provision of a mounting for a valve of this general character which embodies yielding means for holding the valve in proper sealing engagement within its seat.

A further object of the invention is the provision of such a valve which is secured to a rotating shaft, this shaft being journaled in floating bearings yieldingly and adjustably held by opposed spring devices.

A further important object of the invention is the provision of a tapered valve having rotation on a vertical axis, the closeness of fit between the tapered surfaces of valve and valve seat being accurately adjustable by raising or lowering of the valve.

Numerous other objects of the invention will be apparent as it is better understood from the following description, which, taken in connection with the accompanying drawing, discloses a preferred embodiment thereof.

Referring to the drawing:

Figure 1 is a longitudinal, sectional view of a valve and its associated parts illustrating an embodiment of the present invention, the mounting element of the valve being shown relative to the casing of a vacuum chamber;

Fig. 2 is a plan sectional view taken substantially along the line 2—2 in Fig. 1; and

Fig. 3 is a plan sectional detail taken substantially along the line 3—3 in Fig. 1.

In Figs. 1 and 2, there is disclosed for purposes of illustration of the invention, a tapered valve 21, having spaced can carrier pockets 22 for the reception of cans 23. This valve is mounted upon a vertically disposed shaft 24, a key 25 insuring

The valve 21 rotates adjacent a vacuum chamber casing 27 which encloses a vacuum chamber 28, the latter being provided with an opening 29 extending through the casing 27. It is through this opening that the containers are introduced into or withdrawn from the vacuum chamber.

A valve seat 31 is secured to the casing 27 and is provided with a semi-circular projecting wall 32 through which an opening 33 is formed. Opening 33 connects with the opening 29 of the vacuum chamber and cooperates therewith to provide communication with a pocket 22 of the rotating valve 21 as the latter is rotated into proper position.

Valve 21 is preferably provided with a tapered peripheral surface 35 which engages with a correspondingly shaped surface 36 formed in the valve seat 31. As illustrated in Fig. 2 the walls 32 of the valve seat extend substantially half way around the peripheral wall of the valve, the contact between these surfaces 35, 36 providing an air-tight sliding closure for the vacuum chamber opening. The valve and its shaft 24 are mounted in floating bearings and slight lateral or horizontal shifting movement may be had under certain conditions as for example when the valve becomes heated and expands during its operation of conveying cans into or out of the vacuum chamber.

There are two floating bearings, one for the top and one for the bottom of the valve shaft 24. In the lower bearing unit a sleeve 41 (Figs. 1 and 3) provides an element for the support of the valve. This sleeve is formed with an upper flange 42 on which a ball bearing unit 43 rests. This unit is partially embedded in a seat 44 formed in the bottom of the valve 21. The bearing unit 43 surrounds the shaft 24 and provides an anti-friction bearing for the rotating valve.

The vertical position of the sleeve 41 determines the closeness of fit between the tapered surface 35 of the valve and the corresponding tapered surface 36 of the valve seat and this vertical position may be altered to provide proper working conditions. For this purpose the sleeve is threaded for the reception of an upper adjusting collar 46 and a lower adjusting collar 47. The upper collar rests upon a washer 48 embedded in and supported by a housing 49 formed as an integral part of the casing 27. This collar 46 is held in predetermined position by a locking collar 51 also threaded on the sleeve. The adjusting collar 47 cooperates with the collar 46 and is in like manner locked in its predetermined position by a locking collar 52 threadedly engaging the sleeve. 110

The collars 46, 47 are spaced from each other a sufficient distance to permit free lateral sliding movement of the sleeve 41 relative to the frame 49. A vertical opening 53 is formed in the frame 49 and is considerably larger than the outer diameter of the sleeve 41 to give the proper clearance.

The upper end of the shaft 24 is held in similar manner so that its upper bearing floats or has slight lateral sliding movement relative to the casing 27. For this purpose a sleeve 55 loosely surrounds the upper end of the shaft and is located within an enlarged recess 56 extending vertically through a frame extension 57 of the casting 27. Sleeve 55 is formed with a flange 58 which fits within a counterbore 59 formed in the frame 57. The upper end of the sleeve 55 is threaded for the reception of an adjusting collar 61 and a locking collar 62. This adjustment of the collar 61 on its sleeve is made for the purpose of providing a proper distance between the collar face and the flange 58 of the sleeve 55 to permit easy lateral shifting of the sleeve with the shaft 24 within the recess 56. While the valve 21 is supported on the sleeve 41, the shaft 24 is held in proper vertical position by means of the key 25 and also a collar 63 pinned to the upper end of the shaft.

The exact lateral position of the shaft 24 relative to the casing 27 at any particular time is determined by yielding spring members associated with both upper and lower bearings. This is independent of the vertical adjustment of the shaft just referred to. Mechanically these spring holding features are the same for both top and bottom of the shaft and will now be described in detail.

For the lower bearing the frame 49 is formed with a laterally extending chamber having upper and lower walls. A bearing block 64 is located within this chamber and has sliding, lateral movement between the parallel chamber walls. This block surrounds the sleeve 41, the sliding movement of the block and also shaft and valve being in and out or toward and away from the casing 27.

The block 64 is provided with opposed counterbores 65, 66 the former on the inside or the side next to the casing 27. One end of a spring 67 is located within the bore 65, the opposite end extending within the inside of a hollow adjusting nut 69 threadedly secured within the frame 49. A locknut 71 threadedly engages this adjusting nut and clamping against the frame, holds the nut 69 in predetermined position. In like manner one end of a spring 75 is located within the bore 66, its opposite end being engaged by a hollow adjusting nut 76 threaded within the frame 49 and held in adjusted position by a locknut 77. Thus the opposing springs 67, 75 working in opposite directions or against one another, provide the yieldable holding feature for the lower end of the shaft 24.

For the upper floating or yielding bearing the frame 57 is similarly recessed to provide a laterally extending chamber having upper and lower parallel walls for the reception of a block 92 slidably located therein, this block surrounding the upper sleeve 55. Opposed bores 93, 94 are formed in this block 92 and adjacent ends of opposed springs 95, 96 extend therein. Spring 95 is on the inside or adjacent to the casing 27 and is held in adjusted position by a hollow adjusting nut 97 threadedly engaged in the frame 57. Its adjusted position is maintained by a lock-

nut 99. The spring 96 is engaged at its opposite end within a hollow adjusting nut 101 threadedly secured in the frame, this nut being held in adjusted position by a locknut 103.

Springs 67, 95 control the outward pressure 80 exerted through their respective blocks 64, 92 and provide for the lateral thrusts in one direction for the shaft 24 and its valve 21. In a similar manner, springs 75, 96 exert an inward holding influence against the blocks 64, 92.

The compression upon the several springs being independently controlled, it will be evident that the amount of outward or inward pressure or the resulting balanced pressures against the shaft make possible a fine adjustment of holding forces for the valve. When the vacuum chamber 28 is vacuumized, atmospheric pressure acting upon the outer wall of the valve 21 tends to force it tightly against the cooperating tapered walls of the valve seat 31 and without the compensating features just described of the sliding spring held bearings, this atmospheric pressure would cause excessive wear on the valve seat and require an excess of driving force to rotate the valve. With the adjustment of the springs 67, 95 for greater compression, however, the required partial compensation is made to properly hold the valve inwardly against its seat with just sufficient force to seal the chamber opening. As the valve 21 expands, after becoming heated in operation, yielding of the springs 75, 96 automatically takes place compensating for the resulting change in position of the valve center.

It is desirable that provision be made for 110 removing the cans 23 from the valve pockets 22 and for this purpose a swinging finger 111 (Figs. 1 and 2) is located within each pocket 22. These fingers are each mounted upon a vertical shaft 112 extending through the valve and the upper 115 end of each shaft carries an arm 113. The outer end of the arm rotatably carries a cam roller 114 which operates within a groove 115 of a stationary face cam 116 mounted just above the valve 21 and secured to the frame 57.

The valve 21 may be rotated in any suitable manner, as by driving through its shaft 24, a gear 117 (Fig. 1) on the lower end of the shaft providing a form of driving connection for this purpose.

It is thought that the invention and many of its attendant advantages will be understood from the foregoing description and it will be apparent that various changes may be made in the form, construction, and arrangement of the parts without departing from the spirit and scope of the invention or sacrificing all of its material advantages, the form hereinbefore described being merely a preferred embodiment thereof.

I claim:

1. In an apparatus for vacuumizing containers, the combination of a vacuum chamber having an opening therein, a rotating can carrier valve for closing said opening, a rigid valve seat interposed between said chamber and said valve, and means associated with said valve and yielding in directions towards and from said chamber to maintain the tightness of the valve on its seat.

2. In an apparatus for vacuumizing containers, the combination of a vacuum chamber having an opening therein, a rotating can carrier valve mounted in floating bearings for closing said opening, a rigid valve seat interposed between said chamber and said valve, and spring yielding means associated with said bearings for con-

trolling the engagement between said valve and said seat.

3. In an apparatus for vacuumizing containers, the combination of a vacuum chamber having an opening therein, a tapered, rotating can carrier valve for closing said opening, a rigid valve seat having tapered valve engaging surfaces interposed between said chamber and said valve, adjustable devices for bringing the tapered surface of said valve closer to or farther from the tapered surface of said valve seat, and yielding means associated with said valve for controlling the engagement between it and said seat.

4. In an apparatus for vacuumizing containers, the combination of a vacuum chamber having an opening therein, a rotating can carrier valve for closing said opening, a rigid valve seat interposed between said chamber and said valve, resilient means associated with said valve for controlling the engagement between it and said seat, and means for adjusting the effective operation of said resilient means.

5. In an apparatus for vacuumizing containers, the combination of a tapered rotating valve having can carrier pockets, a rigid valve seat associated with said valve and having tapered valve engaging surfaces, adjustable devices for raising and lowering the said valve relative to said seat, and spring yielding means associated with said valve for controlling the engagement between it and said seat.

6. In an apparatus for vacuumizing containers, the combination of a tapered rotating valve having can carrier pockets, a rigid valve seat associated with said valve and having tapered valve engaging surfaces, adjustable devices for raising and lowering the said valve relative to said seat, spring yielding means associated with said valve for controlling the engagement between it and said seat, and means for adjusting the compression of said springs to vary the effective operation of said yielding means.

7. In an apparatus for vacuumizing containers, the combination of a casing enclosing a vacuum chamber, a tapered valve having can carrier pockets mounted adjacent said casing for moving

cans relative to said vacuum chamber, a valve seat secured to said casing and having tapered valve engaging surfaces, a vertically disposed shaft on which said valve is mounted, floating bearing members slidably carried by said casing and mounted on said shaft, and yielding means interposed between said casing and said bearing members for controlling the engagement between said tapered valve and valve seat surfaces.

8. In an apparatus for vacuumizing containers, the combination of a casing enclosing a vacuum chamber, a tapered valve having can carrier pockets mounted adjacent said casing for moving cans relative to said vacuum chamber, a valve seat secured to said casing and having tapered valve engaging surfaces, a vertically disposed shaft on which said valve is mounted, floating bearing members slidably carried by said casing and mounted on said shaft, and opposed spring yielding means supported by said casing and operating against opposite ends of said bearing members for controlling both the inward pressure of the said valve against said seat and the outward movement of the same away from its seat to partially counteract the effect of atmospheric pressure on said valve when said chamber is under vacuum.

9. In an apparatus for vacuumizing containers, the combination of a casing enclosing a vacuum chamber, a tapered valve having can carrier pockets mounted adjacent said casing for moving cans relative to said vacuum chamber, a valve seat secured to said casing and having tapered valve engaging surfaces, a vertically disposed shaft on which said valve is mounted, floating bearing members slidably carried by said casing and mounted on said shaft, opposed spring yielding means supported by said casing and operating against opposite ends of said bearing members for controlling both the inward pressure of the said valve against said seat and the outward movement of the same away from its seat to partially counteract the effect of atmospheric pressure on said valve when said chamber is under vacuum, and independent adjustment devices for said spring means.
